UNITED STATES PATENT OFFICE.

CHARLES A. WALTERS, OF MARION, IOWA.

CARPENTER'S SQUARE.

Application filed April 20, 1921. Serial No. 463,016.

To all whom it may concern:

Be it known that I, CHARLES A. WALTERS, a citizen of the United States, residing at Marion, in the county of Linn and State of 5 Iowa, have invented certain new and useful Improvements in Carpenters' Squares; and I do hereby declare the following to be a full, clear, and exact description of the invention, such as will enable others skilled 10 in the art to which it appertains to make and use the same.

The object of this invention is to produce a steel square for carpenter's use, whereby the ordinary workman, without technical 15 training, may perform all the framing operations in the structure of a building, easily and rapidly, and without needing to refer to other tables or data.

The novel mechanical features of the 20 square are found mainly on the face thereof, and relate principally to the framing of roof structures. The tables, directions, and other data on the back of the square relate to other parts of a building, as well as the roof. -

25 The invention is fully disclosed in the description and claims following, reference being had to the accompanying drawings, in which:—

Fig. 1 is a view of the face of the square, 30 but with considerable data omitted, for the sake of clearness of illustration. Fig. 2, is an enlarged view, showing the corner of the square, and full details within that area. Fig. 3 shows the opposite end of the blade, 35 with full details. Fig. 4 is a view of the back of the square, but illustrating a table for braces (even numbers only), to avoid excessive crowding of figures. Fig. 5 shows the corner of an enlarged square (full-sized), and a fragment of the end of the tongue, with a complete brace-table indicated.

The square comprises the usual 24-inch body or blade A, and the 16-inch tongue B. 40 The blade is preferably two inches wide as shown in Fig. 2, and the tongue $1\frac{1}{8}$ inch wide, this being the finished thickness of practically all so-called 2-inch lumber. The 45 graduations at the edges do not differ essentially from those in general use.

On the face of the blade, which is the side shown in Figs. 1, 2 and 3, is stamped all the information that a carpenter needs in framing a roof. It is to be understood that a 50 "common rafter" is a long one, reaching from the "plate" to the ridge; a "hip" or

"valley" rafter is one disposed diagonally thereto, and a "jack" rafter is one extending from the plate to the hip rafter.

The pitch and form of the roof being of 60 course shown in the architect's plans, the builder, in framing the roof, must determine the following facts or dimensions:

The correct length and shape of every rafter in the roof. The accurate plotting 65 of the angles for all the various cuts. The span and pitch of the roof being already ascertained from the architect's plans, all this data may be determined from the square itself.

In a vertical row down the blade is disposed a series of enclosing figures C, quite 70 similar in outline to a nut, and therefore called "nut-shells." The points of these enclosing figures coincide with inch-marks on 75 the square. In a lune at this end of each enclosing figure is stamped in fractional form the pitch corresponding to a line drawn from its respective inch-mark, at the edge of the square, to the 12-inch mark at 80 the edge of the tongue. As roof-pitches vary indefinitely, sixteen of such pitches are indicated in this manner, varying by one inch intervals of rise from $\frac{1}{8}$ to $\frac{3}{4}$ pitch. In the main body of the enclosing figure, and disposed vertically, are the letters A, B, C, D, 85 E and F. To the left of these letters, are the index letters S S (sheathing and shingles, as fully explained hereafter), set to be read by turning the blade horizontally. 90 In handling the square a workman naturally grasps the blade with his right hand, and holds it with the tongue uppermost. The most of the data in the enclosing figures is accordingly stamped to be read in this convenient manner.

The numbers to the right of the index letters A and B denote decimal, for any designated pitch, the length in inches of common, and of hip and valley rafters, respectively. The total length of the rafter is accordingly determined mathematically in feet (instead of by stepping it off by the square) by multiplying this number, in any case, by the run of the roof in feet, and dividing by 12. That the workman need never err in this manner, the rule is printed at length directly under the enclosing figures.

The length of the first, that is to say, the shortest, jack rafter, to be set on 16 inch 110 centers, is shown at the right of the index letter C. If set 24 inches on centers, the

same appears at the right of the index letter D. This spacing of rafters is almost universal. The length of the first jack rafter being ascertained, the lengths of succeeding ones is found by merely adding this sum successively, or multiplying, as set forth specifically on the blade of the square, in the last line. The angle for the side-cut of these jack rafters is determined by the numbers at the right of the index letters E, as specified on the blade, third line. The angle for the side cut of hip or valley rafters is determined by the numbers at the right of F. For sheathing and shingles in gables, and the like, the numbers at the right of S S are taken, according to the respective pitch, and as specified in the fourth line on the blade. This means that the workman is to lay the square ($\frac{1}{4}$ pitch, for example) on the edge of the rafter, with 9" of the tongue and 10" of the blade at the rafter corner, and cut on the line scratched at 10, for the correct side cut of a jack rafter.

It is to be noted that none of the lengths include the projection or overhang for eaves and cornice. The length measured from the extreme upper end of the rafter to a line projected vertically from the outside of the plate is the correct length. This is clearly illustrated by the diagram at the end of the blade, and the accompanying explanation. This is stamped on the square, as a perpetual reminder, since nothing is more common than for rafters to be laid out without "squaring up the heel", and in consequence it does not fit accurately on the plate, and gaps at the ridge. The diagram also illustrates by dotted lines the actual, geometrical "rise" of a roof, which is sometimes confused in the workman's mind with its extreme altitude.

It will be evident that by this construction, after the rule printed on the blade has been familiarized, every figure for every length and angle, is directly under the workman's eye as he places his square on the timber according to the designated pitch, and is always co-ordinated with the pitch. Instead of hunting over the length and breadth of the blade and tongue for scattered figures, he finds them all "in a nutshell".

On the back of the square is stamped a simplified board and timber measure; a rule for computing the number of shingles for a roof, and a table for the cutting of braces. In the board and timber measure, it will be understood that the numbers in the second column denote inches in cross-section, the inch marks on the square indicate feet, and the numbers below the inch marks represent the product or measure in square feet and

inches. In the brace table on the blade the upper numbers between the horizontal lines denote the lengths of the sides of the triangle, and the lower numbers, the hypotenuse, which is the length of the brace, expressed in feet, inches and decimals thereof. In the corner is a diagram D to illustrate the cutting of braces to correspond with the table below. This table extends through nearly the whole length of the tongue, and shows in feet, inches and decimals of an inch the exact extreme length of braces, at 45 degree angles for sides ranging from 1 $\frac{1}{2}$ feet to 11 feet, at 3-inch intervals. In operating with this side of the square uppermost, the workman naturally holds the square by the tongue, and to render the reading of the data convenient, it is all disposed so as to be read with the square in this position.

Having thus described my invention, I claim:

1. A carpenter's square having stamped thereon a row of enclosing figures C, pointed at one end, whose points coincide with the inch-marks on the square, a different roof-pitch being inscribed in each figure, and numerals with indexes to denote corresponding rafter-lengths and various roof measurements and angle cuts.

2. A carpenter's square stamped with a row of outline figures pointed at inch-marks on the square, a different roof-pitch inscribed in each, adjacent numerals to denote the appropriate lengths of common, hip and valley, and jack rafters, placement of the square for side-cuts of hip, valley and jack rafters, and shingles and sheathing in gables, index characters adjacent to said several numeral designations, and explanatory matter on another member of the square explaining the numerical data by reference to said index characters.

3. A carpenter's square with a vertically disposed row of outline figures stamped on the blade, with points at the inch marks, varying roof-pitches inscribed therein near said points, adjacent numerical data to denote rafter-length with relation to said pitches, and the placement of the square for rafter side-cuts, index characters to distinguish such data, and explanatory descriptive matter inscribed on the blade, all of said matter being disposed to be read with the tongue erect and the blade uppermost.

In testimony whereof I affix my signature in presence of two witnesses.

CHARLES A. WALTERS.
